Decorative looking glass
Patented 28th July 1853

Res. 586

Thomas Barry, of New York, N. Y.

Assignor to }

North, Chase & North, of Philadelphia, Pa.

Letters Patent No. 586 - Dated July 26th 1853,

The schedule referred to in these Letters Patent and making part of the same

To all whom it may concern:

Be it known that I, Thomas Barry, of the City, County, and State of New York, have invented a new and ornamental design for a cooking stove, and I do hereby declare that the following is a full and exact description thereof reference being had to the accompanying drawings, and to the letters of reference marked thereon.

Fig 1, is a drawing of the side plate and oven door.

Fig 2, is a drawing of the plate in front of the fire chamber.

Fig 3, is a drawing of the upper front plate, in front of the oven.

Fig 4, is a drawing of the end door of the fire box.

a, b, c, d, e, f, g, h, are ornaments, arranged on the plates as represented in the drawings.

i, k, are mouldings.

Des 586

2

What I claim as my invention, and desire to secure by Letters Patent, is the design and configuration of the mouldings and ornamental work, as herein described, forming an ornamental design for a cooking stove.
